CLAIM

The ornamental design for an overhead transmission conductor cable, as shown and described.

DESCRIPTION

FIG. 1 is a perspective view of a first embodiment of an overhead transmission conductor cable, according to our new design;

FIG. 2 is a side view thereof;

FIG. 3 is an end view thereof; and

FIG. 4 is a sectional view taken on line 4-4 of FIG. 2.

FIG. 5 is a perspective view of a second embodiment of an overhead transmission conductor cable, according to our new design;

FIG. 6 is a side view thereof;

FIG. 7 is an end view thereof; and

FIG. 8 is a sectional view taken on line 8-8 of FIG. 6.

FIG. 9 is a perspective view of a third embodiment of an overhead transmission conductor cable, according to our new design;

FIG. 10 is a side view thereof; and,

FIG. 11 is an end view thereof.

In the drawings, the broken lines are for the purpose of illustrating environment only and form no part of the claimed design.
